UNITED STATES PATENT OFFICE.

FRANK YOKEL, OF PITTSBURGH, PENNSYLVANIA, ASSIGNOR TO PITTSBURGH LAMP, BRASS & GLASS COMPANY, OF PITTSBURGH, PENNSYLVANIA.

DESIGN FOR A COMBINED LAMP-STANDARD AND DESK ARTICLE.

50,438.

Specification for Design.

Patented Mar. 6, 1917.

Application filed December 2, 1916. Serial No. 134,768. Term of patent 3½ years.

To all whom it may concern:

Be it known that I, FRANK YOKEL, a citizen of the United States, residing at Pittsburgh, in the county of Allegheny and State of Pennsylvania, have invented a new, original, and ornamental Design for a Combined Lamp-Standard and Desk Article, of which the following is a specification, reference being had to the accompanying drawing, forming part thereof.

The figure is a perspective view of the combined lamp-standard and desk article illustrating my new design.

I claim:—

The ornamental design for a combined lamp-standard and desk article, as shown.

FRANK YOKEL.
